UNITED STATES PATENT OFFICE.

SIGURD PEARSON, OF HIBBING, MINNESOTA.

COMBINED STEAM-SHOVEL DIPPER.

Application filed September 20, 1923. Serial No. 663,809.

To all whom it may concern:

Be it known that I, SIGURD PEARSON, a citizen of the United States, residing at Hibbing, in the county of St. Louis and State of Minnesota, have invented certain new and useful Improvements in Combined Steam-Shovel Dippers, of which the following is a specification.

This invention relates to a new and improved steam shovel dipper and more specifically to a dipper adapted to cleanly dump its contents when the dipper itself is located at widely varying angles.

In strip mining operations and other similar types of excavating work, very large steam shovels have been evolved using dippers having a capacity of as high as eight cubic yards. They are handled upon long booms or dipper sticks and are capable of discharging their contents upon the bank of the cut or excavation at a point as high as forty feet above the level upon which the shovel car is located. In such operations it is sometimes desirable to discharge the material into cars located upon the floor of the cut. There is thus a very wide difference in the angle at which the dipper is held when discharging into cars on the tracks in the cut from than when discharging into cars upon tracks at the top of a forty-foot bank. Due to the weight of the material, it is impractical to dump the load into cars in the cut by raising the shovel at any very great distance above the cars.

Shovels of usual type are approximately cubical in form with a door upon the bottom, this door usually being in a plane approximately parallel to that of the dipper stick. Such dippers discharge properly in cars upon the bank where the dipper stick is horizontal or not materially above or below this position. However, when discharging into cars upon the pit bottom, the front of the dipper and the bottom are both at approximately 45 degrees to the horizontal. Under these circumstances, there is a tendency for a large portion of the load to remain upon the dipper front and not discharge.

Certain types of dippers have been evolved in the endeavor to solve this problem as, for example, by hinging the front to serve as a dumping opening and also by making the bottom at an angle to the dipper stick and to the dipper sides. While such constructions may add to the dumping ability in

some positions, they are not as efficient as the usual type of dipper when the latter is dumped in its proper position.

It is an object of the present invention to provide a dipper adapted for dumping upon the pit floor or upon the pit bank.

It is a further object to provide a dipper of this character in which a plurality of the dipper walls are hinged for discharge purposes.

It is also an object to provide a dipper in which the plurality of moving walls are so interconnected that they move in unison.

It is an additional object to provide a dipper which may be adjusted so that but a single side is open for dumping purposes.

Other and further objects will appear as the description proceeds.

I have illustrated a preferred embodiment of my invention in the accompanying drawings, in which—

Figure 1 is a side elevation of the dipper in closed position, a portion being broken away to show the latch construction; 80

Figure 2 is a front view of the dipper, a portion being a section upon line 2—2 of Figure 1; and

Figure 3 is a side elevation of the dipper in open position.

The dipper as shown comprises the dipper body having the sides 11 and back 12, the back or rear being secured to the dipper stick 13. The bottom 14 is carried by hinges 15 which are pivoted at 16 to the rear of the dipper. The dipper front 17 is pivoted to the sides 11 at 18. The front may be provided with any usual type of teeth 19.

The dipper front 17 is provided with the rearwardly extending portions 20 which are connected by links 21 to the upwardly extending ears 22 of the dipper bottom 14. The sides 11 are provided with the guide plates 23 which co-operate with guide plates 24 on the dipper front to form a rigid guiding and thrust receiving connection.

The dipper front is provided with the latch plate 25 with which the latch 26 carried by the dipper bottom co-operates. This latch is operated by a usual rope or cable 27. The guide plates 23 and the co-operating portions of the dipper front are provided with registering belt or rivet holes 28, the purpose of which will be discussed hereafter.

The dipper, as shown in the drawings, is

- particularly adapted for discharging its contents upon the pit floor. When so discharging, the dipper stick 13 is inclined downwardly approximately at an angle of 5 45 degrees. In this position, if the front were rigid, much of the material would remain upon the front and not be discharged. However, with the pivoted front connected to the pivoted bottom, as shown in Figure 3, 10 when the latch 26 is withdrawn, the weight of the material swings open both front and bottom and there is a clean dump.
- Both the front and bottom portions would open without the use of the link 21. It is 15 essential, however, for a proper closing of the dipper that both bottom and front swing to the closed position at the same instant so that the latch will catch. This simultaneous closing is assured by the links 21.
- 20 When it is desired to use a dipper for loading on top of the banks, it is unnecessary to have the front open as the bottom will be approximately horizontal. Therefore, when preparing the dipper for this use, the links 25 21 will be removed and the dipper front secured to the guide plates 23 by passing bolts through the co-operating holes 28. In this condition, the dipper dumps as a cubical dipper of ordinary construction.
- 20 It will be understood that there is seldom need for rapid change from pit loading to bank loading, each type of loading being carried on for a considerable period until the nature of the cut or work requires a 25 change. Thus this addition or removal of the links 21 need only take place at relatively great intervals and thus does not militate against the usefulness of the dipper.
- It is to be understood that the specific embodiment shown is by way of example only and I contemplate such changes and modifications to meet varying conditions as may come within the scope of the appended claims.
- 45 I claim:
1. A steam shovel dipper comprising a fixed portion, a plurality of movable wall portions, and interlocking latching means carried by said movable portions.
- 50 2. A steam shovel dipper comprising a fixed portion, a plurality of movable wall

portions, interlocking latching means carried by said movable portions, and means connecting said portions whereby they are constrained to move in unison.

55

3. A steam shovel dipper comprising a fixed portion, a plurality of movable wall portions, and means whereby one of said portions may be rigidly connected to the fixed portion.

60

4. A steam shovel dipper comprising a fixed rear and side wall portion and movable front and bottom portions.

65

5. A steam shovel dipper comprising a fixed rear and side wall portion and movable front and bottom portions, the front portion being hingedly connected to the sides and the bottom to the rear portion.

70

6. A steam shovel dipper comprising a fixed rear and side wall portion and movable front and bottom portions, the adjacent edges of the bottom and front being the free edges thereof.

75

7. A steam shovel dipper comprising a fixed rear and side wall portion, movable front and bottom portions, the adjacent edges of the bottom and front being the free edges thereof, and latch means carried by the front and bottom adapted to maintain them in closed position.

80

8. A steam shovel dipper comprising a fixed rear and side wall portion, movable front and bottom portions, and links connecting the movable portions whereby they are constrained to move in unison.

85

9. A steam shovel dipper comprising a fixed rear and side wall portion, movable front and bottom portions, and means whereby the front portion may be rigidly connected to the fixed portion.

90

10. A steam shovel dipper comprising a fixed rear and side wall portion, movable front and bottom portions, removable links connecting the movable portions whereby they are constrained to move in unison, and related bolt holes in the front and fixed portions whereby the front portion may be rigidly connected to the fixed portion.

95

Signed at Hibbing, Minnesota, this 10th day of September, 1923.

SIGURD PEARSON.
